HEYMAN ROSENBERG, OF NEW YORK, N. Y.

ART OF FASTENING SHEETS TOGETHER.

1,299,232.

Specification of Letters Patent.

Patented Apr. 1, 1919.

Application filed April 16, 1917. Serial No. 162,488.

To all whom it may concern:

Be it known that I, HEYMAN ROSENBERG, a citizen of the United States, residing at New York, in the county of New York and 5 State of New York, have invented certain new and useful Improvements in the Art of Fastening Sheets Together; and I do hereby declare the following to be a full, clear, and exact description of the invention, such as 10 will enable others skilled in the art to which it appertains to make and use the same.

This invention relates to improvements in the art of fastening together sheets of metal and other like relatively thin sheets of 15 material.

The object in view is to easily, quickly and permanently fasten together in a simple and inexpensive manner a plurality of sheets of relatively thin material such as 20 sheet iron and the like.

With this and other objects in view, as will in part be stated and in part hereinafter become apparent, the invention comprises certain improved steps and combinations of 25 steps in the art of fastening together relatively thin sheets of material as will be subsequently specified and claimed.

In the accompanying drawing,

Figure 1 is a view in side elevation of a 30 screw such as is particularly well adapted for carrying out the preferred combination of steps of the present improvement in the art of fastening together relatively thin sheets.

Fig. 2 is a sectional view through two sheets with a tool indicated in elevation in position for beginning the first step of the art or process.

Fig. 3 is a similar view of the same with 40 the parts in the position during the carrying out of the process such as may be designated as the completion of the first step.

Fig. 4 is a view similar to Fig. 3 of the parts after the tool has been removed.

Figs. 5 and 6 are similar views, the former showing an intermediate step, and the latter the product upon completion of the process.

Fig. 7 is an enlarged, detail fragmentary view of the parts as seen in Fig. 6.

Fig. 8 is a view similar to Fig. 6 showing more than two sheets connected together.

In the art of fastening together metallic sheets, various methods have been proposed and the one usually preferred for such construction work as cornices and metal trim on buildings, housings for blowers, and else-

where where for various reasons it is impracticable or undesirable to use solder, has been to employ bolts of the machine screw type engaging the plates at one face by the 60 head of the bolt and at the other face by the nut of the bolt. Much difficulty has been experienced in fastening together sheets in this manner, both from the fact that it is frequently difficult to provide access to the 65 nut, and from the fact that variations in temperature and vibrations cause the nut to loosen.

The object of the present invention is to overcome all these difficulties by employing 70 a method of connection which eliminates the need for machine thread, eliminates the nut, and produces a connection which is stable in every respect and which throughout long and careful tests has proved to remain absolutely tight notwithstanding vibrations and 75 temperature variations.

The steps of the present improved process or art, and one specific sequence or combination thereof, may more readily be rendered clear by reference to such structural formations as are effected by the process as, for example, such as is illustrated in the accompanying drawing in which 1 indicates the body of a screw whose thread 2 is of the 80 form and pitch of what is known as a "wood screw" by which is meant the commercial iron screw adapted for use in wood. The body 1 tapers to a point at one end and at the other end is provided with the usual 85 notched head 3. In other words, the screw is of the shape of the ordinary commercial wood screw, but differs therefrom in the fact that the screw is made of steel and that the thread 2 is hardened preferably by a 90 special case-hardening process, as by the known cyanid process or its equivalent. The structure of the screw, therefore, consists essentially of a body whose thread is hardened while there is no attempt at or need 95 for hardening of the body. Incident to the treatment in hardening the thread 2, the surface of the body of the screw may also be hardened, but that is an incidental result and not one necessary to the effective operation of the screw, the essential need being 100 that the thread itself shall be hardened and provided with a cutting edge, such as seen at 2' in Fig. 7, and that the body of the screw shall terminate in a tapered end with 105 the thread correspondingly tapering.

The sheet material to be connected together

may have quite a wide variation in thickness, but is usually sufficiently thin to be susceptible of perforation by some form of punching apparatus whether manually or machine operated. Perhaps the widest field of utility of the present improvement in the art finds application in the connecting of relatively thin sheets of material such as galvanized iron, ordinary sheet iron, and tin coated or plated iron, commonly known as sheet tin, and like thin sheets of material, but it will become obvious that the invention is just as applicable to sheets of material having greater thickness. For the sake of illustration, however, I have selected the thinner sheets for disclosure of the invention herein, and to this end it will be noted that the two sheets of metal 4 and 5 are arranged in contact face to face, and the tool 6, which in the present instance is an ordinary hand punch having the usual limiting shoulder 7, is arranged with its point in contact with the plate 4 in position for penetrating the two plates. A blow on the punch 6, as by a hammer not illustrated or force otherwise applied, causes the punch 6 to penetrate the sheets 4 and 5 until the punch assumes the position indicated in Fig. 3, resulting in the perforation of the two sheets and the formation of a bur, on each, the two burs being nested as clearly seen at 4' and 5' in Fig. 4. The penetrating point portion of the punch 6 is of less diameter than the diameter of a circle such as would touch diametrically opposite points of any helix of the larger portion of the thread 2, and is preferably of approximately the size of the body 1, so that the screw cannot be introduced into the opening surrounded by the burs 4' and 5' except by revolving the screw and thus causing the thread 2 to cut a corresponding or female thread in the burs 4' and 5'. As the thread 2 is tapered to the end of the body 1 the thread has an excellent opportunity to enter and get an effective start in the cutting of a female thread. For thin sheets of metal, it is usually sufficient to provide an ordinary hand-operated screw-driver for revolving the screw and thus threading the same down from the position indicated in Fig. 5 to the position indicated in Fig. 6, that is, the screw is threaded home and made tight. In doing so, the female thread is cut in the inner face of the bur 4' across the edge of the bur and across the edge of the bur 5' which slightly underhangs the edge of the bur 4', so that the thread of the screw assumes the position with respect to the bur seen in detail in Fig. 7. The head 3 resting on the upper surface of the plate 4 and the thread 2 engaging the edge of the bur 5' coöperate to prevent separation of the sheets.

It should be observed that in the carrying out of the process or art one of the essential steps is the penetration or cutting of the

metal of the sheets by the thread of the screw without appreciably varying the condition of that thread. This feature of the improved art cannot be accomplished with an ordinary wood screw or any screw having a soft thread. My experience after long and thorough testing has been that a screw having a soft thread may be used to connect sheet metal, but the soft threads usually suffer as much cutting away or abrasion as do the sheets which the thread engages, and the result is that the soft threaded screw will not hold, whereas the result of the present improved art including that penetration or cutting of the metal of the sheets which occurs from the use of hardened threads is such that the sheets are permanently secured together against disconnection under the most severely trying conditions.

It should be obvious that this invention is not limited to the art of connecting any specific number of sheets, since the same steps in the same sequence may be carried out for connecting more than two sheets, as clearly indicated in Fig. 8, wherein the sheets 4^a, 5^a and 8 are connected by the screw 1^a by the carrying out of the process just described.

What I claim is:—

1. A process of securing together a plurality of sheets of material comprising perforating the sheets in a manner forming nested burs surrounding the perforation and threading a screw having a hardened thread through the burs to a position with the thread in engagement with the burs in a manner causing the thread to cut into the material of the sheets for retaining the sheets against separation.

2. A process of securing together a plurality of metallic sheets comprising forming an entering opening through the sheets and forcibly threading a screw having a hardened thread into said opening, the screw having a thread proportioned with respect to the entering opening to outstand beyond the same and to cut into the material of the sheets.

3. A process of securing together a plurality of metallic sheets comprising perforating the sheets to form an entering opening therethrough and forcibly threading into said opening a screw whose thread is hardened and of substantially high pitch and proportioned with respect to the opening such as to have the edges of the thread extend laterally beyond the opening and to cut into the material of the sheets.

4. A process of securing together a plurality of metallic sheets comprising forming an entering opening through the sheets, placing in the opening the smaller end of a tapered screw and forcibly threading the screw home into the opening, the opening being of less diameter than the main portion of the thread of the screw, and the thread

of the screw being of harder material than the sheets and cutting into the sheets as the screw is forcibly threaded home.

5. A process of securing together a plurality of metallic sheets comprising forming an entering opening through the sheets, positioning in the opening the pointed portion of a screw of the conventional wood screw shape but having a hardened thread and 10 forcibly threading the screw into the opening, the opening being of less diameter than that of the larger portion of the screw thread so as to cause the thread of the screw to cut into the material of the sheet metal.
- 15 6. A process of securing together a plurality of metallic sheets comprising perforating the said sheets and forming nested burs in the material of the sheets surrounding the perforation, placing in the perforation the point portion of a screw of the shape of a conventional wood screw and having a hardened screw thread, the perforation being of less diameter than the larger portion of the screw thread, and forcibly 20 threading the screw through said perforation to a position with the head of the screw
- 25

engaging that one of the metallic sheets first approached by the screw while the thread of the screw engages and is embedded in the material of the burs.

30

7. In the art of fastening together sheets of metal, forming an entering opening through a plurality of such sheets in contact with each other, placing in said opening the tip of a screw conforming generally in body 35 and thread contour with that of a wood screw and having the thread hardened and extending substantially from the tapered tip to the head of the screw, the entering opening being of substantially no greater diameter than the body of the screw, and forcibly rotating the screw until the hardened thread thereof cuts its way in the material of the sheets to a point of contact of the head of the screw with one of the sheets.

40

In testimony whereof I affix my signature in presence of two witnesses.

DISCLAIMER

1,299,232.—*Heyman Rosenberg, New York, N. Y.* ART OF FASTENING SHEETS TOGETHER. Patent dated April 1, 1919. Disclaimer filed March 28, 1932, by the patentee and the exclusive licensee, *Parker-Kalon Corporation*.

Hereby enter their disclaimer of said claims 1, 2, 3, 4, 5, 6, and 7 of said United States Letters Patent No. 1,299,232, which claims are in the following words, to wit:

“1. A process of securing together a plurality of sheets of material comprising perforating the sheets in a manner forming nested burs surrounding the perforation and threading a screw having a hardened thread through the burs to a position with the thread in engagement with the burs in a manner causing the thread to cut into the material of the sheets for retaining the sheets against separation.

“2. A process of securing together a plurality of metallic sheets comprising forming an entering opening through the sheets and forcibly threading a screw having a hardened thread into said opening, the screw having a thread proportioned with respect to the entering opening to outstand beyond the same and to cut into the material of the sheets.

“3. A process of securing together a plurality of metallic sheets comprising perforating the sheets to form an entering opening therethrough and forcibly threading into said opening a screw whose thread is hardened and of substantially high pitch and proportioned with respect to the opening such as to have the edges of the thread extend laterally beyond the opening and to cut into the material of the sheets.

“4. A process of securing together a plurality of metallic sheets comprising forming an entering opening through the sheets, placing in the opening the smaller end of a tapered screw and forcibly threading the screw home into the opening, the opening being of less diameter than the main portion of the thread of the screw, and the thread of the screw being of harder material than the sheets and cutting into the sheets as the screw is forcibly threaded home.

“5. A process of securing together a plurality of metallic sheets comprising forming an entering opening through the sheets, positioning in the opening the pointed portion of a screw of the conventional wood screw shape but having a hardened thread and forcibly threading the screw into the opening, the opening being of less diameter than that of the larger portion of the screw thread so as to cause the thread of the screw to cut into the material of the sheet metal.

“6. A process of securing together a plurality of metallic sheets comprising perforating the said sheets and forming nested burs in the material of the sheet surrounding the perforation, placing in the perforation the point portion of a screw of the shape of a conventional wood screw and having a hardened screw thread, the perforation being of less diameter than the larger portion of the screw thread, and forcibly threading the screw through said perforation to a position with the head of the screw engaging that one of the metallic sheets first approached by the screw while the thread of the screw engages and is embedded in the material of the burs.

“7. In the art of fastening together sheets of metal, forming an entering opening through a plurality of such sheets in contact with each other, placing in said opening the tip of a screw conforming generally in body and thread contour with that of a wood screw and having the thread hardened and extending substantially from the tapered tip to the head of the screw, the entering opening being of substantially no greater diameter than the body of the screw, and forcibly rotating the screw until the hardened thread thereof cuts its way in the material of the sheets to a point of contact of the head of the screw with one of the sheets.”
